DESTEROLATION

Kenneth C. D. Hickman, Rochester, N. Y., assignor, by mesne assignments, to Eastman Kodak Company, Rochester, N. Y., a corporation of New Jersey

No Drawing. Application August 7, 1946,
Serial No. 688,963

4 Claims. (Cl. 260—397.2)

1

This invention relates to an improved method of removing sterols from oil concentrates, and portions thereof, and particularly to a process which crystallizes sterols so they may be easily removed by filtration.

Sterols are usually present in vegetable oils to an extent not exceeding 1%. Whenever the tocopherol fraction is concentrated from a vegetable oil, for example by high-vacuum unobstructed-path distillation or by saponification of glyceride fractions, most of the sterols are found in the tocopherol concentrate, the sterol percentage frequently being above 30%. The term "oil concentrate" as used in this application is defined as a vegetable oil which has been put through a process to obtain a tocopherol concentrate containing in excess of 5% sterols.

Past practice for sterol removal has been to add 3 or 4 parts of acetone or 10-15 parts of methyl alcohol to the oil concentrate and cool to temperatures of the order of -20° C. After allowing to stand for about 15 hours the precipitated sterols are removed by filtration. This method leaves a substantial proportion of the sterols in solution.

This invention has for its object to provide a process for separation of sterols from oil concentrates by the use of minimum quantities of solvent. Another object is to produce sterols of high purity. A further object is to specify a procedure by which sterols may be rendered less soluble. A still further object is to improve the state of the art. Other objects will appear hereinafter.

These and other objects are accomplished by my invention which includes contacting a sterol-containing fatty oil with relatively small quantities of methanol, or ethylene glycol to render the sterol fraction less soluble and more easily crystallized.

In the following examples and description I have set forth several of the preferred embodiments of my invention but it is to be understood that these are given for the purpose of illustration and not in limitation thereof.

In the course of my investigation of ways to remove sterols from oil concentrates I have discovered that methanol and ethylene glycol act upon sterols to render them less soluble in oil concentrates. The mechanism by which this is accomplished is not clear but apparently the sterols enter into loose combination with the additive. This is evidenced by the fact that sterols crystallize in the form of needles from acetone solutions whereas alcohol-sterol crystals are in the form of plates.

2

The precipitant effect of methyl alcohols or ethylene glycol cannot be attributed to their presence as solvents. The quantities added are small, for example 1 to 10%, and most of the alcohol adds to the sterol fraction and is precipitated upon subsequent filtration.

In amounts below about 10% by weight based on the weight of the oil being treated, methyl alcohol and ethylene glycol dissolve in the oil, forming a single liquid phase. The single liquid phase system has the advantages of effecting intimate contact between all of the solvent and the oil and greatly lessens the fire hazard which is present when larger amounts of solvent are employed forming a two phase liquid system.

If the material to be desterolated contains over 20% sterols, I find it more convenient to desterolate in two steps. Oil concentrates of over 20% sterol content will usually be semi-solid or solid due to the precipitation of excess sterols. Such an oil may be heated slightly above the temperature required to effect solution of the sterols and then cooled slowly over a period of 24 to 72 hours to room temperature. Slow cooling, preferably without stirring, allows some of the sterols to precipitate in uniform crystal size and structure. The material may then be further processed by passage through a grinder, such as a simple meat grinder, to release any oil entrained in the interstices of the sterol crystals. The resulting mushy mixture is filtered to remove the separated sterols.

The filtrate from the above operation, or the original oil concentrate if less than 20% sterols are present, is contacted with methyl alcohol, or ethylene glycol in an amount not exceeding an equal weight of the oil concentrate and preferably about 10% by weight of the oil concentrate. Contact is preferably made at a temperature near the vaporizing temperature of methyl alcohol, or ethylene glycol, depending on which is used. The effect of increasing temperature is to improve crystal quality and yields. Lower temperature or not heating at all results in improved separation over the prior art but the yield and quality of the crystals are inferior to those produced by hot mixing with the additive.

If the initial sterol content of the oil concentrate is over 20%, alcohol or glycol may be added in a single-step process. However, in this event greater quantities of tocopherols are enmeshed in the sterols and filtration becomes a time-consuming step. The two-step process is therefore preferable.

The material is cooled slowly until the sterols are precipitated, the time of cooling depending

on the quantity of oil. For 50-gallon quantities the time preferably will be about 48 to 72 hours, preferably lagging the vessel during the first 18 hours. For 200-gram quantities, 4 hours is a suitable cooling time.

In general it may be said that the higher the temperature and the slower the cooling, within reasonable limits, the more uniform will be the crystal structure.

After the material has cooled the precipitated sterols are separated, preferably by filtration. If the mixture is of a solid nature due to large amounts of sterols, a grinding step may precede the filtration.

Lower temperatures can be employed, especially when the stearine content is low as in soybean concentrate, with the attendant benefit of producing a filtrate with lower sterol content. The filtration can be carried on at a higher temperature when the stearine content of the oil is high, as in a tocopherol concentrate obtained by high-vacuum distillation of deodorizer sludge. This will not remove as much sterol from the oil but the sterol will be of a higher purity with a smaller quantity of stearine present.

There are marked advantages to be gained by my method of desterolization. First, large volumes of solvent are not required. Second, an elaborate cooling system is not necessary, although cooling the mixture below room temperature will increase yields. Thirdly, a single liquid phase system is formed with a resultant enhancement of desterolization and avoidance of fire and explosion hazards encountered where a solvent layer is present.

Example 1.—1 kg. soybean concentrate containing 28% sterols was heated in a beaker to 70° C. and 40 ccs. of methanol (about 3.2% by weight of alcohol based on the weight of concentrate treated) were added with rapid stirring. The beaker was set aside in the cold room (4° C.) for four hours, the contents of the beaker were broken up with a spatula and filtered on the Buchner funnel. There resulted a clear brown filtrate containing 7.1% sterols.

Example 2.—A soybean concentrate produced by subjecting soybean oil to high-vacuum unobstructed-path distillation weighing 181 kg., containing 156 mg./g. of tocopherol and 34.4% sterol was heated to 90° C. and cooled slowly for 3 days. When the concentrate reached room temperature it was ground in a meat grinder and filtered on large Buchner funnels. The filter cake amounted to 67.7 kg. containing 71.5 mg./g. of tocopherol and 68.3% sterol. The filtrate weighed 111 kg. and had 204 mg./g. of tocopherol and 14.4% sterols.

The filtrate was heated to 65° C. and 4% by weight of methanol added below the surface while stirring. The container was lagged for 18 hours and cooled slowly for 2 more days. The cooled mass was reground as before and filtered on a Buchner funnel. The cake weighed 11 kg. and contained 63.9% sterols and 77.6% mg./g. of tocopherol. The filtrate was a clear, sparkling oil

amounting to 97.3 kg. with 208 mg./g. of tocopherol and 6.27% sterols.

Example 3.—A tocopherol concentrate obtained by the high-vacuum distillation of deodorizer sludge weighing 641 g. and containing 11.3% sterols was filtered in a basket centrifuge and 79 g. of cake removed. A 462-gram portion of the filtrate was heated to 63° C. and 18.6 g. of methyl alcohol calculated as 4% by weight of alcohol based on the weight of filtrate being treated was added below the surface while the mixture was being stirred. The mixture was allowed to stand overnight, after which the material was filtered. The cake weighed 51.6 g. and the filtrate 404 g., 7.7% of which was sterol.

Example 4.—A 200 gram sample of tocopherol concentrate produced by high-vacuum unobstructed-path distillation of soybean oil and containing 10-12% sterols was heated to 65° C. and 8 grams of ethylene glycol (calculated 4% by weight ethylene glycol based on weight of concentrate being treated) was added below the surface. The mixture was stirred for 2 minutes and cooled slowly to room temperature. Filtration removed 7.3 grams of sterols.

What I claim is:

1. The method of desterolating an oil concentrate which comprises dissolving in said concentrate from 1-10% by weight, based on the weight of said concentrate, of a substance selected from the group consisting of methyl alcohol and ethylene glycol and thereby precipitating sterols from said concentrate.
2. The method of desterolating an oil concentrate which comprises dissolving in said concentrate from 1-10% by weight, based on the weight of said concentrate, of methyl alcohol and thereby precipitating sterols therefrom.
3. The method of desterolating an oil concentrate which comprises dissolving in said concentrate from 1-10% by weight based on the weight of said concentrate, of a substance selected from the group consisting of methyl alcohol and ethylene glycol, at a temperature below the vaporization temperature of said substance, cooling the resulting mixture and thereby precipitating sterols therefrom, and thereafter separating the precipitated sterols from the liquid out of which said sterols precipitated.
4. The method of desterolating an oil concentrate which comprises dissolving in said concentrate from about 3% to about 4% by weight, based on the weight of said concentrate, of methyl alcohol and thereby precipitating sterols therefrom.

UNITED STATES PATENTS

Number 2,046,345 Name SCHIEGER Date July 7, 1936

Certificate of Correction

Patent No. 2,515,041

July 11, 1950

KENNETH C. D. HICKMAN

It is hereby certified that error appears in the printed specification of the above numbered patent requiring correction as follows:

Column 3, line 63, for "77.6% mg./g." read *77.6 mg./g.*; column 4, line 9, before the word "calculated" insert an opening parenthesis; line 10, after "treated" insert a closing parenthesis;

and that the said Letters Patent should be read as corrected above, so that the same may conform to the record of the case in the Patent Office.

Signed and sealed this 17th day of October, A. D. 1950.
